UNITED STATES PATENT OFFICE.

FRANK M. RUTTEN, OF CRARY, NORTH DAKOTA.

YIELDING CLEVIS FOR PLOWS.

No. 834,412.

Specification of Letters Patent.

Patented Oct. 30, 1906.

Application filed March 19, 1906. Serial No. 306,719.

To all whom it may concern:

Be it known that I, FRANK M. RUTTEN, a citizen of the United States, residing at Crary, in the county of Ramsey and State of North Dakota, have invented certain new and useful Improvements in Yielding Clevises for Plows; and I do hereby declare the following to be a full, clear, and exact description of the invention, such as will enable others skilled in the art to which it appertains to make and use the same.

My invention has for its object to provide an improved clevis for use in connection with plows and other implements; and to this end it consists of the novel devices and combinations of devices hereinafter described, and defined in the claims.

The improved device is illustrated in the accompanying drawings, wherein like characters indicate like parts throughout the several views.

Figure 1 is a plan view showing my improved clevis applied to a frame of a plow. Fig. 2 is a vertical section taken through the clevis on the line $x^2 x^2$ of Fig. 1, the parts being on a larger scale than Fig. 1 and some parts being left in full. Fig. 3 is a transverse section taken on the line $x^3 x^3$ of Fig. 2; and Fig. 4 is a view corresponding to Fig. 1, but illustrating a slightly different application of the draft connection thereto.

The numeral 1 indicates the forward ends of a pair of plow-beams that are rigidly connected by a bracket 2 and to which bracket 35 is rigidly secured a horizontally-disposed flanged bar 3, having perforations 4. The clevis is made up chiefly of a hollow spring-casing 5, that is approximately rectangular in exterior cross-section, and a pair of quite 40 heavy metallic straps 6, that embrace the opposite flat sides of said spring-box. At its open end the spring-box 5 has two of its side plates extended so as to form laterally-spaced hinge-lugs 7, that are perforated to 45 pass a coupling-bolt 8. Each of the four sides of the spring-box 5 is formed with a long longitudinally-extended slot 9. A nutted bolt 10 is passed through seats in the rear ends of the two straps 6 and through 50 one or the other pair of the oppositely-disposed slots 9. Within the spring-box 5 is a heavy coiled spring 11, that reacts against the closed end of said box and against the bolt 10. This spring therefore tends to 55 force the spring-box into a retracted position between the straps 6, as shown in the draw-

ings and especially in Fig. 2. The bolt 10 therefore acts as a follower to compress the spring 11, and it also serves as a pivot which will prevent angular or oscillatory movements of the spring-casing with respect to the straps 6. The outer ends of the straps 6 are perforated to pass a coupling-bolt 12. The coupling-bolts 8 and 12 at their lower ends are slotted or split to afford seats for pivoted lock-pieces 13, that are normally gravity-held in horizontal or approximately horizontal positions, as shown in Fig. 2, so that they will thereby prevent the said bolts from being worked upward, except when the said 70 lock-pieces are turned into vertical positions.

By means of the bolt 8 the lugs of the spring-box 5 may be directly coupled to the perforated flange 3 4 of the plow-frame. When the spring-box is thus coupled to said 75 flange, the outer edge of the flange bears against the rear edge of said box at 5^a and holds the said box so that it cannot move pivotally with respect to said flange.

By means of the bolt 12 the forward ends 80 of the straps 6 may be pivotally coupled either to an equalizing-beam 14 of a draft-equalizer, as shown in Fig. 1, or to a sheave 15, as shown in Fig. 4. The sheave 15 is intended for use in connection with a draft-chain 16, to one end of which the equalizing-beam 14 of one two-horse evener is 85 attached and to the other end of which an equalizing-beam of another two-horse evener (not shown) would be attached, thereby 90 adapting the plow to be drawn by two teams hitched one ahead of the other.

Some plows have parts corresponding to the perforated flange 3, that extend in a horizontal plane, and others have them extending 95 in a vertical plane. The straps 6 in both instances usually stand in horizontal planes one over the other, and hence an adjustment of the spring-box 5 is required. This may be quickly accomplished by the device 100 described simply by removing the coupling-bolt 10, then removing the spring-casing 5 and giving the same one-fourth rotation and then replacing the same between the straps 6 and replacing the bolt 10 so that the parts 105 are again connected substantially as shown in Fig. 2, but with the lugs 7 of said spring-box turned into vertical planes. The clevis is then adapted for application to a plow-frame or to a single plow-beam which has a 110 vertically-extended perforated flange.

As is evident, the spring 11 affords a cush-

ion which prevents sudden jars and extreme strains in case the horses should lunge suddenly forward or in case the plow is run against an obstruction, such as a stone or 5 root. The spring cushioning device, therefore, prevents breaking of the parts of the plow and the harness under the circumstances above noted, and, furthermore, greatly relieves the horses from sudden 10 strains and makes their work easier than where a rigid connection is employed.

The device is of small cost and is efficient for the purposes had in view.

What I claim is—

- 15 1. In a clevis, the combination with a spring-box, of a pair of straps connected thereto with freedom for pivotal and sliding movements thereon, and a spring within said box reacting against said box and against 20 said straps, substantially as described.
2. In a clevis, the combination with a spring-box having two pairs of diametrically and opposite slots extended longitudinally thereof, and having projecting lugs at 25 its open end, of a spring in said box, a pair of straps embracing the sides of said box, and a

bolt adapted to connect said straps to said box for sliding movements with respect thereto, and which bolt is insertible in either of said two pairs of slots to set the said box 30 and straps in different adjustments with respect to each other, substantially as described.

3. In a clevis, the combination with a spring-box 5 which is approximately rectangular in exterior cross-section, said box having in its four sides the two opposite pairs of longitudinally-extended slots 9 and having also the perforated end lugs 7, a pair of straps 6, embracing the sides of said box, a 40 coupling-bolt 10 passed through the rear ends of said straps and through one or the other pairs of slots 9, and a spring 11 within said box 5 reacting against said box and against said coupling-bolt 10, substantially 45 as described.

In testimony whereof I affix my signature in presence of two witnesses.

FRANK M. RUTTEN.
